Attorney

UNITED STATES PATENT OFFICE.

ARTHUR HERMONE STARRETT, OF ATHOL, MASSACHUSETTS, ASSIGNOR TO THE L. S. STARRETT COMPANY, OF ATHOL, MASSACHUSETTS, A CORPORATION OF MASSACHUSETTS.

STEEL RULE WITH HOLDER.

Application filed October 27, 1921. Serial No. 510,904.

To all whom it may concern:

Be it known that I, ARTHUR H. STARRETT, a citizen of the United States, residing at Athol, in the county of Worcester, Commonwealth of Massachusetts, have invented certain new and useful Improvements in Steel Rules with Holders, of which the following is a specification.

This invention relates to ruler holders, and particularly to a holder for clamping a relatively short ruler so that the ruler may be laid against surfaces which are inaccessibly located for measurement, as for example an inside surface.

The object of my invention is to provide a simple and convenient holder which will permit the ruler to be disposed in a variety of positions according to the character of the surface to be measured.

The construction and operation of my invention is described and illustrated in the accompanying specification and drawings, throughout which like reference characters are correspondingly employed, and the characteristic features of novelty are particularly pointed out in the appended claim. In the drawings:

Fig. 1 is an elevation of a clamp in accordance with my invention.

Fig. 2 is an enlarged view of the handle member, disconnected.

Fig. 3 is an enlarged view of the holder sleeve, disconnected.

Fig. 4 is an enlarged view of the blade clamp.

Fig. 5 is a longitudinal section through the sleeve shown in Fig. 3.

Figs. 6, 7, and 8, are views illustrating the use of the device, and

Fig. 9 is an enlarged section through the assembled device, particularly illustrating the clamping action.

I have indicated at 1 a handle member which may be milled externally as at 2 to provide a convenient gripping surface. At its forward end the handle 1 is reduced, as indicated at 3, to provide a stop shoulder and beyond said shoulder extends as a reduced threaded stem portion 4 adapted to be inserted into a holder sleeve 5 and to engage with a short series of internal threads 6 whereby to detachably connect the handle and sleeve members.

Beyond the thread series 6 the sleeve 5 is provided through one face thereof with an angularly extending slot 7 for the reception of a ruler R which is adapted to be lodged in said slot with one face thereof seated against an inclined wall 8 at the closed end of the sleeve.

The ruler is clamped against the seat 8 by a clamping plunger 9 which is slidable within the sleeve 5. The plunger 9 is reduced as indicated at 10 and terminates in a clamping face 11 which is inclined at an angle corresponding to that of the seat 8.

Surrounding the reduced portion 10 of the plunger is a coil spring 12 which abuts the enlarged head 9 thereof at one end and at its opposite end abuts an internal shoulder 12' on the sleeve 5.

The ruler R is adapted to be inserted in the slot 7 and clamped to its seat 8 by the beveled face 11 of the plunger 9 which plunger is pushed forwardly into clamping position by the stem portion 4 of the handle 1 when said handle is threaded into the sleeve 5. The abutment of the shoulder 3 against the rear end of the sleeve 5 limits the forward movement of the handle into the sleeve. The spring 12 is compressed when the plunger 9 is moved forwardly by the handle. When the handle is unscrewed, the spring expands and moves the plunger 9 rearwardly in the sleeve, relieving the clamping pressure on the ruler R so that said ruler may be removed from the slot 7.

The closed end of the sleeve 5 is beveled, as indicated at 13, preferably at an angle to the seat 8 so that the ruler will be brought up closely to the surface to be measured when the beveled end 13 of the sleeve is laid against said surface.

Various modifications in the form and construction of my device may obviously be resorted to all without departing from the spirit of my invention if within the limits of the appended claim.

What I therefore claim and desire to secure by Letters Patent is:

A rule holder comprising a hollow sleeve having its forward end closed, an inclined seat adjacent its forward end and having a correspondingly inclined slot adjacent said seat and communicating with the hollow in said sleeve and extending from the top of

said seat towards but terminating short of the bottom of said sleeve and into which a rule may be entered to assume a variety of positions relatively to the longitudinal axis of the sleeve, and a clamp adjustable within said sleeve and having a clamping face inclined to correspond to said seat and engageable with the rule at any point along its

several marginal edges to releasably clamp the rule against said seat.

In testimony whereof I affix my signature in presence of two witnesses.

ARTHUR HERMONE STARRETT.

Witnesses:

WILLIAM E. CRAMER,

WALTER L. MAYHEW.
